UNITED STATES PATENT OFFICE.

GEORGE E. TARNOW, OF CHICAGO, ILLINOIS.

FASTENING DEVICE FOR RIBBON BOWS AND THE LIKE.

985,075.

Specification of Letters Patent. Patented Feb. 21, 1911.

Application filed March 22, 1909. Serial No. 484,881.

To all whom it may concern:

Be it known that I, GEORGE E. TARNOW, a citizen of the United States, residing at Chicago, county of Cook, State of Illinois, 5 have invented a certain new and useful Improvement in Fastening Devices for Ribbon Bows and the Like, and declare the following to be a full, clear, and exact description of the same, such as will enable others skilled 10 in the art to which it pertains to make and use the same, reference being had to the accompanying drawings, which form a part of this specification.

In my prior Patent, No. 887,149, granted 15 May 12, 1908, I have disclosed a novel form of pin for holding and securing bows or the like. In the patented arrangement the bow is intended to be tied in place upon the body member of the pin.

20 The present invention relates to this same class of devices and it has for its object to provide a simple and novel device for firmly holding a ribbon bow or the like which has already been made up and securing it to the 25 clothing or hair of a wearer.

The various features of novelty whereby my invention is characterized will herein-after be pointed out with particularity in the claim; but, for a full understanding of 30 my invention and of its object and advantages, reference may be had to the following detailed description taken in connection with the accompanying drawing, wherein:

Figure 1 is a rear view of a ribbon bow 35 secured upon a device arranged in accordance with a preferred form of my invention; Fig. 2 is a section on line 2—2 of Fig. 1; and Fig. 3 is a front view of the device showing the attaching pin open.

40 Referring to the drawing, A represents a body member, the general shape of which is preferably long and flat. The central portion of the body member is preferably removed so as to provide an elongated slot a. 45 The body member may be made in any de- 50 sired way as, for example, by stamping it from sheet metal. I do not desire to limit myself to a body member stamped from sheet metal, however.

55 B is a pin of any suitable kind, connected at one end to the member A, and adapted to secure said member to the clothing or hair of a wearer. In the particular embodiment shown this pin is of the U-shaped variety 55 pivotally mounted at its yoke in lugs b bent up from the body member and arranged to

engage at its free ends with a pair of hooks b¹ also integral with the body member. The members b and b¹ lie upon the same side and at opposite ends of the body member.

C is a clasp hinged at one end to one edge of the body member as at c. The hinge may conveniently be formed by means of ears a¹ and c¹ which are respectively integral with the members A and C. It will be seen that the clasp swings about an axis at right angles to the pivotal axis of the member B. The free end of the clasp is provided with a hook or catch c² which is adapted to interlock with one of the bounding edges of the slot a. The edge a² is preferably cut away as at a³ for a distance equal to the width of the clasp so that when the clasp is locked in position the inner surface of its free end will lie flush with the edge a². The clasp is preferably 75 made of spring metal so that after it is placed in a locked condition it will remain so. The size and shape of the clasp is such that it will firmly clasp the knot x of a ribbon bow X against the body member when the bow is laid upon the member and the clasp snapped in position. It will be seen that a portion of the knot will be forced into the slot a of the body member and therefore the bow will be held firmly and prevented 80 from being displaced or becoming awry either by reason of its weight or from any other cause. It will also be seen that after the clasp has been closed over the bow, the 85

bow exerts a pressure which forces the catch 90 more firmly against the edge of the body member with which it interlocks, and the danger of the accidental opening of the clasp is therefore very small. Where the device is intended to hold other objects than 95 ribbon bows, the clasp is, of course, designed so as to grip firmly the particular object for which it is intended. Furthermore, the pin B may take any other form than that shown which will adapt it to the use for which the 100 device is desired.

It will now be seen that I have provided a simple and novel holding and fastening device for ribbon bows or the like which is capable of holding bows which have already 105 been tied or made up so that it is unnecessary for the user to tie the bow upon the device or disarrange it when its removal is desired.

Having now fully described my invention, what I claim as new and desire to secure by 110 Letters Patent is:

In a device of the character described, a

long straight narrow flat body member having a slot extending longitudinally therein, a pin on one side of said member for securing it in place, a bowed clasp overlying the 5 opposite side of said member and extending transversely thereof, a hinge connecting one end of the clasp with said member, adjacent to one of the long edges thereof, and a catch on the free end of said clasp constructed and 10 arranged to coöperate with the bounding edge of said slot farthest removed from said

hinge so as to lock the free end of the clasp to said member, said clasp being of a size and shape such as to cause the clasp wholly to conceal that portion of the body member 15 which it overlies.

In testimony whereof, I sign this specification in the presence of two witnesses.

GEO. E. TARNOW.
